US00D768142S

(12) **United States Design Patent** (10) **Patent No.:** **US D768,142 S**
(45) **Date of Patent:** **** Oct. 4, 2016**

(54) **ELECTRONIC DEVICE WITH GRAPHICAL USER INTERFACE**

(71) Applicant: **Samsung Electronics Co., Ltd.**, Suwon-si (KR)

(72) Inventors: **Seunguk Lee**, Seoul (KR); **Junghyun Shim**, Yongin-si (KR)

(73) Assignee: **SAMSUNG ELECTRONICS CO., LTD.**, Suwon-Si, Gyeonggi-Do (KR)

(**) Term: **14 Years**

(21) Appl. No.: **29/483,478**

(22) Filed: **Feb. 28, 2014**

(30) **Foreign Application Priority Data**

Aug. 29, 2013 (KR) 30-2013-0044385

(51) **LOC (10) Cl.** **14-04**

(52) **U.S. Cl.**

USPC **D14/485**

(58) **Field of Classification Search**

USPC D14/485-495

See application file for complete search history.

(57) **CLAIM**

The ornamental design for an electronic device with graphical user interface, as shown and described.

DESCRIPTION

The FIGURE is a front view of an electronic device with graphical user interface showing our new design.

The broken lines showing the electronic device and portions of the graphical user interface are for environmental purposes and form no part of the claimed design.

1 Claim, 1 Drawing Sheet
